UNITED STATES PATENT OFFICE.

ALFRED D. CRESSLER, OF WASHINGTON, DISTRICT OF COLUMBIA.

UNITED COAL-STORAGE ELEVATOR SYSTEM.

Application filed March 15, 1919. Serial No. 282,825.

To all whom it may concern:

Be it known that I, ALFRED D. CRESSLER, a citizen of the United States, residing at Washington, District of Columbia, have invented certain new and useful Improvements in United Coal-Storage Elevator Systems, of which the following is a specification.

This invention relates to a united elevator system for the storage of coal, and is especially designed for the purpose of providing a structure which will effectually eliminate the possibility of losses of value from spontaneous combustion at any and all times during the storage of the coal within said structure, regardless of the depth of the pile therein and the period it remains in its stored position.

The main object of the invention is to provide a simple, strong, durable, economical and thoroughly efficient united elevator structure, preferably of concrete, that will absolutely prevent spontaneous combustion, heating, or ignition of the coal during its storage within the structure.

It is a well established fact that when coal has been stored in large piles of more than six feet in depth, either in outdoor exposure or within bins or other structures, and especially when the coal is of a friable nature, and is mixed with fine particles which approach that of dust, said dust being dangerous, particularly if it is mixed with lump coal of such a size that the interstices permit the flow of a moderate amount of air to the interior, and also if the coal so stored is bituminous, that such coal remaining in its stored condition for more than six weeks or two months is liable to spontaneous heating or combustion. It is also well known that in a small pile of coal the slowly developed heat can be readily dissipated by convection and radiation and very little rise in temperature results, but if the dissipation of the heat is restricted, as in a large pile densely packed, the temperature within the pile rises continuously, hence when the storage conditions are such as to allow warming of the coal to a temperature of about 100 degrees C., the rate of oxidation becomes so great that the heat developed in a given time ordinarily exceeds the heat dissipated, and the temperature rises until, if the air supply is adequate, the coal takes fire.

It is, therefore, important to guard against

even moderate heating of the coal, either spontaneous or from an external source, and thereby avoid and eliminate the excessive losses of value which have heretofore occurred from the spontaneous combustion of stored coal, hence it is the purpose of my invention to solve the problem of storing coal in piles of any suitable or desirable depth by providing a novel structure which will absolutely prevent spontaneous combustion and thereby prevent the serious losses and destruction occasioned thereby.

A further object of this invention is to provide a united elevator structure including a series of novel coal storage receptacles in which all coal may be safely stored for any suitable or desirable period of time in different sizes or grades, or in mixed condition, and at the same time effectually prevent spontaneous combustion during such storage.

A further object of the invention is to so construct my improved elevator structure that each receptacle will be provided with inlets at the top portion thereof to receive the coal, and outlets for the discharge of the coal at the bottom portion thereof, said inlets and outlets being normally sealed air-tight when in their closed position.

A further object of this invention is to provide means, in connection with each of the receptacles constituting the united elevator structure, for filling and distributing the coal within the receptacle without any serious or undue breaking or crushing of the coal into small particles, such as usually results in the ordinary method of filling deep receptacles with coal, and means supported on the top of each receptacle for operating the said filling and distributing means.

Another object of the invention is to provide in connection with my improved united elevator coal storage structure, automatically operated fire extinguishing means, which will effectively extinguish a fire which may possibly occur from any cause whatsoever within the coal receptacle.

Still further objects of my invention are to furnish an economical and safe means for storing coal at established terminals and various points of distribution and consumption by railroads, plants utilized for federal use, manufacturers, public utility companies, and for local distribution to private consumers; to enable the operators to maintain

a uniform rate of production at the mines so as to provide the miners with uniform working conditions, thereby insuring a greater number of regular days' work throughout the year; to insure the fuel consumers a supply of coal at all times; and also to permit the railroads to utilize their cars and equipment to the best advantage.

The foregoing and such other objects as may appear from the ensuing description are attained by the novel features of construction, combination, arrangement and location of parts hereinafter more fully described, illustrated in the accompanying drawings, and particularly pointed out in the claims appended hereto, it being understood that slight changes in the form, proportion, and minor details of the construction may be resorted to without departing from the spirit or sacrificing any of the advantages of the invention.

In the accompanying drawings which form a part of this specification it will be seen that:

25 Figure 1 is a view partly in elevation and partly in vertical section of a nest or battery of four storage and delivery coal pockets or bins showing a homogeneous structure embodying my invention.

30 Figure 2 is a slightly enlarged vertical section of one of the storage bins, said section being taken through one of the inlets and outlets secured to the bin, and showing the coal chute or conductor partly in section 35 and partly in elevation.

Figure 3 is an elevation of the top portion of one of my improved bins, showing the bin broken away near its top portion, and

Figure 4 is a vertical section taken 40 through one of the discharge outlets, showing in section the bottom portion of the bin broken away.

Similar numerals of reference are employed to designate like or equivalent parts 45 wherever found throughout the several views.

In carrying out this invention it will be understood that my novel coal storage bins or receptacles 1, 2, 3 and 4, as shown in 50 Figure 1, may be formed of any desired material, such as iron, steel, concrete or reinforced concrete; of any suitable shape, size or dimensions, and may be nested together in any desirable manner to form a 55 homogeneous structure, provided each coal bin or storage receptacle constitutes an absolutely air-tight structure when in its closed condition, but, as shown, my improved structure is preferably formed of suitable concrete material 2', which may be reinforced 60 by metallic inserts at any desirable points throughout the structure, and each storage bin is preferably supported at a suitable distance above its foundation by the supporting columns 3', to permit a railway car,

truck or other suitable conveying means to be moved beneath a discharge outlet 4', for the purpose of receiving the coal discharged therefrom and conveying it to the point of utilization or any other desirable place.

Each of the storage bins is provided with a hopper-like bottom portion 5, preferably formed integral with the walls of the structure, said hopper portion serving to direct and feed the coal to an air-tight outlet 4 suitably secured to the bottom of the bin, each outlet consisting of an inner hollow casing of any suitable shape having depending walls 5' provided at its lowermost discharge end with a swinging gate 6 adapted to normally close its open end, said gate being supported and carried by stub shafts 7 mounted in an outer casing 8' provided with stuffing box 9, adapted to receive one of the stub shafts, the other stub shaft being mounted in a boss 9' formed on said outer casing, the open lowermost end portion of the outer casing being provided with a closure 10 hinged to said outer casing at one side thereof, the inner peripheral portion of the closure being recessed for the reception of a sealing gasket 11 formed of asbestos or any other desirable material, and its central portion formed with a depending screw threaded recess adapted to receive the securing screw 12 for rigidly and tightly securing the closure to the lower end of the outer casing, said screw 12 passing through a threaded opening in an arm 13, which is also hinged to the outer casing 8' and supported at one end thereof by a link 14, pivotally secured to an extension 15 formed on said outer casing, one of the said stub shafts 7 having a lever 10' secured thereto for manipulating the swinging gate 6.

Each coal storage bin is provided at its top portion with a central vertical extension 16, and suitably secured and sealed to the upper surface of said extension is a coal inlet metallic frame 17, of any suitable shape, preferably annular in form, provided with a cover 18 pivoted at one side thereof and adapted to be swung around laterally, as shown in dotted lines, Fig. 3, said cover having a plurality of recesses formed around its peripheral portion adapted to receive the upper end portion of a plurality of swinging bolts 19, each bolt being pivotally secured at its lower end at 20 to the base portion of the inlet frame, and the upper threaded end portion of each of the bolts being provided with a securing nut 20' for tightly securing the cover to the inlet frame, said cover being recessed around its lower peripheral face to receive a sealing gasket 21 of any desirable material. Supported within the top portion of the extension 16 is a metallic plate 22, and mounted on the pins or shafts 23 for supporting said plate are the pulleys 24, over each of which passes a suit-

able cable or rope 25 for the purpose hereinafter described. Slightly below said plate within, and at one side of the extension 16, is supported in any desirable manner by 5 bearings formed in the extension a windlass 26, to which one end of each cable or rope 25 is secured, and on the outer end of the windlass shaft 27 is mounted a suitable windlass operating gear wheel, clutch or pulley 10 28, connected with means leading to an electric motor (not shown) or any other suitable or desirable operating means forming no part of this invention.

Mounted on said shaft 27, on the outside 15 of the extension 16, is a ratchet wheel 29 adapted to be engaged by a pawl 30 suitably mounted on the outside of said extension.

The inner peripheral top portion of the coal inlet frame is recessed at 31 for the purpose 20 of receiving the flanged peripheral portion 32 of the top section 33 of a telescopic chute or coal conductor 34, so that the upper flanged portion of the top section will rest flush with the upper surface of the inlet 25 frame, while the peripheral shouldered portion 35 of said top section rests in contact with the inner surface of the inlet frame.

The top section of the telescopic chute or 30 coal conductor 34 is provided with an outwardly flaring top portion 36, and a depending tubular lower portion 37, said chute or conductor consisting of a series of tubes 38 of varying lengths and dimensions slidably connected to each other, and to the lower- 35 most tube section at each side thereof are suitably secured at 39 the cables or ropes 25.

It will be readily perceived that when the coal bin is empty the chute or conductor will be positioned substantially in the manner 40 shown in bin 2, Fig. 1, and as shown in Fig. 2, so that when it is desired to fill the bin with coal the inlet cover securing means are disengaged, the cover swung to one side and the windlass operating means is started 45 when the coal is dumped into the inlet receiving chute or coal conductor, said operating means being so timed and regulated that as the coal is discharged through the lower- 50 most section of the conductor and spreads out within the bin, the series of tubes constituting said conductor will be gradually raised by the cables which wind around the windlass until the bin is properly filled, when all of the tube sections surround the lower- 55 portion of the uppermost section and rest within the extension 16 formed at the top of each bin, after which the pawl 30 will be disengaged from the ratchet wheel 29, so that the conductor or chute 34 will be automatically lowered as the coal is discharged from the bin, so that when the bin is entirely empty the conductor rests in its proper position for recharging or filling the bin, as 60 will be readily understood.

By reference to Fig. 1, bin 4, it will be

seen that I may provide my storage bins, if desired, with a fire extinguishing system in the event of the possible firing of the coal by spontaneous combustion, said system consisting of a water supply pipe 40 connected 70 with a circular pipe 41 located within the bin at its top portion, and depending from said bin is a plurality of pipes 42, each being provided with a series of water discharge outlets 42' which are normally sealed 75 by fusible plugs, which readily fuse at a certain predetermined temperature, thereby opening the series of discharge outlets, and permitting the water to freely flow into the bin until it is sufficiently flooded to thoroughly quench the fire within. It will be seen that this bin 4 is provided at its bottom portion with a hopper-shaped metallic member 43 provided with a series of minute perforations to permit the water to drain 80 therethrough, and into a chamber 44 formed between said hopper-shaped member and the bottom of the bin, from whence the water may be carried off and emptied through the drain pipe 45 connected with the bottom of 85 the bin. The upper wall of this bin 4 is provided with an air vent 46, within which is seated any well known automatically operated valve (not shown), which will allow the air to escape when the pressure within 90 the bin is sufficient to unseat said valve.

It will be understood that my improved structure may be erected with any suitable or desirable number of coal receptacles or bins joined together in a united structure of any convenient or desirable shape or contour, or the coal bin or receptacle may be erected in a single structure, and these structures may be located at the coal mines, railway depots, stations, or in cities, manufacturing plants, yards, or any other place desired.

Having thus described my invention, what I claim and desire to secure by Letters Patent is:

1. A united coal elevator storage structure, comprising a receptacle adapted to prevent spontaneous combustion of the coal stored therein, an air-tight sealed inlet mounted on the top of the receptacle, a discharge outlet mounted at the bottom of said receptacle, an air-tight casing fixedly secured to the bottom of the receptacle independent of and surrounding said outlet, and air-tight sealing means carried by the casing and adapted to seal said casing below the discharge outlet.

2. A coal elevator storage structure of the character described, comprising an air-tight receptacle adapted to prevent spontaneous combustion of the coal stored therein, said receptacle being provided with an integral hopper shaped bottom portion, an air-tight sealed inlet at the top of the receptacle, a discharge outlet mounted at the bot- 130

tom of the receptacle, an air-tight casing secured to the bottom of said receptacle independently of the outlet and surrounding said outlet, and air-tight sealing means secured to said casing and adapted to seal the casing below the discharge outlet.

3. A coal elevator storage structure of the character described, comprising a receptacle adapted to prevent spontaneous combustion of the coal stored therein, said receptacle having a central extension at its top portion, an air-tight sealed inlet centrally mounted on the top of said extension, a central discharge outlet mounted at the bottom of the receptacle, an air-tight casing mounted at the bottom of the receptacle independently of the outlet and surrounding said outlet, and air-tight sealing means secured to the casing and adapted to seal said casing below the outlet.

4. A coal elevator storage structure of the character described, comprising a receptacle adapted to prevent spontaneous combustion of the coal stored therein, said receptacle being formed with a central hollow vertical extension at its top, an air-tight sealed inlet centrally mounted on the top of said extension, discharging means mounted at the bottom of the receptacle, an air-tight casing fixedly secured to the bottom of the receptacle independently of the discharging means and surrounding said means, and air-tight sealing means secured to the casing and adapted to seal said casing below the discharging means.

5. A united coal storage elevator structure, comprising an air-tight receptacle adapted to prevent spontaneous combustion of the coal stored therein and formed with an integral central upright extension, an air-tight sealed inlet mounted on said extension, a telescopic coal conductor fixedly suspended from and carried by said extension, and an air-tight sealed outlet at the bottom of the receptacle.

6. A united coal storage elevator structure, comprising a concrete air-tight coal receptacle formed with a vertical extension at its top, an air-tight sealed inlet frame mounted on said extension, a stationary telescopic coal conductor fixedly mounted within and carried by said frame, and an air-tight sealed outlet centrally secured to the bottom of the receptacle.

55 7. A united coal storage elevator structure, comprising an air-tight coal receptacle formed with an integral central hollow vertical extension at its top, an air-tight sealed inlet frame mounted on said extension, a stationary telescopic coal conductor fixedly suspended from said inlet frame with its upper section resting on and within said frame, and an air-tight sealed outlet centrally mounted at the bottom of the receptacle.

8. A united coal storage elevator structure, comprising an air-tight coal receptacle formed with a central upright extension at its top, an air-tight sealed inlet frame mounted on said extension, a telescopic coal conductor fixedly suspended from said frame, and means supported and carried by the extension for elevating said coal conductor.

9. A united coal storage elevator structure, comprising an air-tight coal receptacle formed with a central upright extension at its top, an air-tight sealed inlet frame mounted on said extension, a telescopic coal conductor fixedly suspended within the receptacle by said frame, and means secured to said conductor and supported within and carried by said extension for elevating the coal conductor.

10. A united coal storage elevator structure, comprising a concrete air-tight coal receptacle formed with an integral central upright extension at its top, an air-tight inlet frame mounted on said extension, a stationary telescopic coal conductor fixedly suspended by said frame within the extension and receptacle, and an air-tight sealed outlet secured to the bottom of said receptacle.

11. A united coal storage elevator structure, comprising an air-tight coal receptacle formed with a central upright hollow extension, an air-tight sealed inlet frame mounted on the top of said extension, a telescopic coal conductor fixedly mounted within said frame by the top section of the conductor resting on the frame, and means supported within and carried by said extension for elevating all of the conductor sections within the extension.

12. A united coal storage elevator structure, comprising an air-tight coal receptacle formed with a central upright extension, an air-tight sealed inlet frame mounted on said extension, a telescopic coal conductor fixedly suspended centrally within the receptacle and mounted on said frame, means carried within the extension for elevating the conductor, and means for permitting the conductor to be lowered by gravity.

13. A united coal storage elevator structure, comprising an air-tight coal receptacle formed with a central upright extension at its top, an air-tight sealed inlet frame mounted on said extension, a telescopic coal conductor fixedly suspended by said frame within the receptacle, means supported within and carried by the extension for elevating the conductor, means carried by the extension for supporting the conductor at any elevated position, and means for permitting the conductor to lower itself within the receptacle.

14. A united coal storage elevator structure, comprising an air-tight coal receptacle formed with a central upright extension at

its top, an air-tight sealed inlet frame mounted on said extension, a coal conductor suspended by said inlet frame, a stationary windlass supported within and carried by 5 said extension, and means connected to said windlass and conductor and carried by the extension for elevating the conductor.

15. A united coal storage elevator structure, comprising an air-tight coal receptacle 10 formed with a central upright extension at its top, an air-tight sealed inlet frame mounted on said extension, a coal conductor fixedly suspended from said frame within the receptacle, a plate supporting pulleys 15 carried within the extension, a windlass mounted in the extension, and cables connected to said conductor and windlass and passing over the pulleys for elevating the conductor.

20 16. A united coal storage elevator structure, comprising an air-tight coal receptacle formed with a central upright extension at its top, an air-tight sealed inlet frame mounted on said extension, a stationary 25 coal conductor suspended by said frame within the receptacle, pulleys supported within and carried by said extension, a windlass mounted within and carried by the extension with a shaft extending through one 30 side of the extension, cables connected with said conductor and windlass for elevating the conductor, and means fixedly supported by the extension and connecting with said

shaft for securing the conductor in varying elevated positions.

17. A united coal storage elevator structure, comprising an air-tight coal receptacle formed with a central upright extension, an air-tight sealed inlet frame mounted on 40 said extension, a stationary telescopic coal conductor mounted on said inlet frame, and means carried by the extension for raising the said conductor within the extension and to automatically lower the conductor within the receptacle.

45 18. A coal storage elevator structure, comprising an air-tight coal receptacle, and an air-tight sealed outlet consisting of discharging means carried at the bottom thereof, an outer casing surrounding the discharging means, and a sealing door hinged to the lower portion of the outer casing below said discharging means.

50 19. A coal storage elevator structure, comprising an air-tight coal receptacle, and an air-tight sealed outlet, said outlet consisting of discharging means carried at the bottom of the receptacle, an outer casing surrounding said means, sealed means carried by the outer casing for operating the 55 discharging means, a sealing door hinged to the lower end of the outer casing, an arm hinged to the lower end of the outer casing, and means for securely locking said door and arm to the said outer casing.

ALFRED D. CRESSLER.
